CLAIM

The ornamental design for a transformable chair enclosure, as shown and described.

DESCRIPTION

FIG. 1 is a front view of a transformable chair enclosure, according to our new design;

FIG. 2 is a back view thereof;

FIG. 3 is a left-side view thereof;

FIG. 4 is a right-side view thereof;

FIG. 5 is a top view thereof;

FIG. 6 is a bottom view thereof;

FIG. 7 is a front, top, right perspective view thereof; and,

FIG. 8 is a right-side view thereof.

The broken lines showing a chair, chair base, table, and steering wheel controller, depict optional environmental structure that form no part of the claimed design. Additionally, the broken lines representing a figure of a person, in FIG. 8, illustrate environmental structure and form no part of the claimed design.
